UNITED STATES PATENT OFFICE

WALTER C. DAVIDSON, OF NORTH CANTON, OHIO, ASSIGNOR TO THE HOOVER COMPANY, A CORPORATION OF OHIO

SUCTION CLEANER

Application filed July 19, 1929. Serial No. 379,418.

This invention relates to suction cleaners in general, particularly to suction cleaner dust bags. Specifically the invention relates to dust bags made from a new and improved filtering material which is characterized by its qualities as an efficient filter for the foreign-matter-laden air which passes therethrough and by the ease of removal of the foreign matter from the bag 5 upon the cleaning thereof.

The object of the invention is the provision of a new and improved dust bag for suction cleaners. Another object is to provide a dust bag for suction cleaners in 15 which the efficiency as a filtering medium is supplemented by the ease of removal of foreign matter collected therein. A further object of the present invention is to provide a dust bag of multi-ply material having a 20 smooth glossy interior.

The efficiency of cloth dust bags as a filtering medium for the dust-laden air which is exhausted from the suction cleaner in the operation thereof, is dependent upon the 25 type of material used in the bag and upon the way or manner in which that material is woven into a fabric. It is the teaching of experience that the best filtering cloth is woven from relatively rough-surfaced yarns 30 made of loosely twisted fibers which are united into a fabric by smooth, hard yarns of relatively small diameter in order to give the resulting fabric sufficient mechanical strength. The best grade of the ordinary 35 filtering cloth is not too tightly woven, for such a condition results in excessive back pressure upon the suction cleaner and a reduction in the cleaning efficiency thereof. On the other hand the fabric must not be 40 too loosely woven for in that case the air will escape therethrough carrying the foreign matter with it. The efficient dust bag is so woven that the foreign matter will be removed as the air passes therethrough by

45 the rough surface of the yarn going to make up that fabric, yet the fabric will not be so tightly woven as to increase excessively the back pressure upon the suction cleaner.

The use of yarn having a rough, harsh 50 surface which is requisite for an efficient

filtering medium is accompanied by the disadvantage that after the foreign matter is removed from the air which passes therethrough it tends to adhere to the cloth and is not easily removed. The usual dust bag, 55 being provided with an opening at one end, is cleaned by shaking the bag with the open end facing downwardly, so that the foreign matter upon being dislodged from the surface of the cloth will fall therethrough. 60 The resistance to elimination caused by the adherence of the foreign matter to the cloth often results in failure of removal and the continued use of the dust bag with the foreign matter deposited thereon; an undesirable 65 condition which results in excessive back pressure in the suction cleaner.

The present invention is characterized by the presence, in addition to the actual filtering material, of an inner layer or ply of 70 smooth, glossy, finished material which is woven on one side of the usual filtering material and serves as an extra ply thereto. The surface formed by the smooth, glossy, 75 material serves as the inside of the bag in the construction thereof and functions to make easier the removal of the foreign matter deposited upon the cloth when the bag is cleaned, as aforescribed.

In the accompanying drawing illustrating 80 a preferred embodiment of the present invention the views are as follows:

Figure 1 is a view of a dust bag constructed in accordance with the present invention and attached to the handle of a suc- 85 tion cleaner.

Figure 2 is a diagrammatical cross section of the dust bag filtering material constructed in accordance with the present invention.

Referring now to Figure 1 in particular a dust bag is shown and is indicated by the reference character 3. An attaching plate 4 is secured to the lower end of the dust bag 3 which is the open end and is provided with 95 attaching means 5 which are adapted to coact with the exhaust outlet of a suction cleaner upon which the bag is positioned to secure the lower end of the bag in place. A supporting strap 6 is secured to the upper 100

end of the dust bag by a pivotal connection 7 and at its upper end to the suction cleaner handle 8 through a swinging connection 9.

The cloth used in the dust bag 3 is constructed in accordance with the present invention in a manner which is illustrated in Figure 2 of the drawing. In Figure 2 a three ply fabric is disclosed which is composed of an outer face or ply 10 comprising 5 yarns 11, 11 etc., which are secured relative to one another by warp face yarns 12 and 13. An intermediate or stuffer ply of the fabric is indicated by the reference character 14 and is composed of yarns 15, 15 etc., of relatively large diameter as compared 10 with the warp yarns and which have a rough fibrous exterior similar in all respects to the yarns 11, 11 of the ply 10, which are secured together into a single ply by means 15 of the small diameter and hard finished warp back yarns 16 and 17. The plies 10 and 14 are similar to those found in all efficient filtering material and form a coarse cloth presenting filtering texture differing 20 in no great respect from the ordinary dust cloth material, being composed merely of large diameter rough surface filler yarns which are secured together by smooth hard small diameter yarns which have no filtering 25 qualities but merely serve to bind the material together and lend tensile strength thereto. According to the present invention however, the ply 18 of material of large diameter which has a smooth glossy and finished surface such as rayon, silk substitute 30 formed from cellulose products or even silk itself, the yarns of which are indicated by the reference characters 19, 19, etc., is affixed to the usual plies 10 and 14. The yarns 35 19, 19 of the ply 18 are secured to the other two plies 10 and 14 by means of warp binder yarns which are indicated on the drawing by the reference character 20.

The operation of the dust bag, constructed 40 in accordance with the present invention, as a filtering medium upon the suction cleaner is as follows: The foreign-matter-laden air which has been exhausted from the exhaust outlet of the suction cleaner into 45 the dust bag at a relatively high velocity builds within the dust bag a positive pressure which is considerably higher than the atmospheric pressure on the outside of the dust bag. The air in passing from the point 50 of high pressure to the point of low pressure must escape through the fabric of the dust bag and in doing so permits the dust cloth to perform its useful function as a filtering medium. The foreign matter carried 55 by the air may be roughly divided into two groups, namely, fine particles such as dust of a small diameter and usually smooth in surface texture, and matter of relatively 60 greater size such as lint and having a rough or coarse texture. It is the latter group 65

which makes the ordinary dust bag so hard to clean because it adheres to the yarns thereof which, like themselves, are also rough. As the dirt laden air passes through the bag cloth, constructed in accordance 70 with the present invention, it first contacts the inner ply thereof which, as aforescribed, comprises the yarn 19 having the smooth glossy surface. The ply 18 being a relatively poor filter permits the smaller 75 particles to pass therethrough but the larger lint particles adhere to the smooth glossy surface of the yarn 19 thereof and do not reach the plies 14 and 10. The finer particles pass through the ply 18 and are removed 80 from the passing air by the plies 10 and 14. The liny foreign particles which so strenuously adhere to the yarns of the plies 10 and 14, because of their rough exterior, thereby making the cleaning of the 85 bag so difficult in the usual dust bag, do not reach these plies in the dust bag constructed in accordance with the present invention but are removed by the inner ply 18.

The cleaning operation of a dust bag 90 constructed in accordance with the present invention is both easy and efficient. The liny foreign matter which has adhered to the inner ply 18 is readily dislodged therefrom because of the smooth glossy exterior of the 95 yarns of that ply. The smaller and finer foreign particles which have been retained by the plies 14 and 10 are not a source of cleaning difficulty even in the usual dust bag and are easily dislodged. The ease of 100 removal of all the foreign particles insures a clean dust bag after each cleaning which in turn aids in the cleaning efficiency of the suction cleaner of which the bag is a part.

It is to be understood that while a preferred embodiment of the present invention 105 has been shown and described any changes may be made in form, construction and arrangement of the parts such as for example, the incorporation of more than two plies of 110 the rough-surface filtering yarns or by the use of a greater number of the smooth surface lint removing yarns, without departing from the spirit of the invention or sacrificing any of the advantages thereof and 115 the right is hereby reserved to make all such changes as fairly fall within the scope of the following claims.

I claim:—

1. A filter member for use in a suction 120 cleaner, formed of multi-ply fabric comprising a ply of material having a rough surface and a surface ply of material having a smooth surface, and warp threads 125 uniting said plies.

2. A dust bag for use in a suction cleaner, 130 formed of multi-ply fabric comprising a ply of material formed of yarns having a relatively rough exterior and a surface ply

of material formed of yarns having a relatively smooth exterior.

3. A dust bag for use in a suction cleaner, formed of multi-ply fabric comprising an outer ply of material having a rough surface and an inner ply of material having a smooth surface, and warp threads uniting said plies.

10 4. A dust filtering member formed of multi-ply fabric comprising a plurality of plies having weft yarns with rough exteriors and a surface ply having weft yarns with a smooth exterior and warp threads uniting said plies.

15 5. A dust filtering member formed of multi-ply fabric comprising a ply of cotton material and a surface ply of rayon material.

20 6. A dust filtering material for use in a suction cleaner, formed of multi-ply fabric comprising a ply having yarns of rough exteriors and a surface ply having yarns of glossy exteriors, said plies being united by hard yarns of relatively small diameter.

25 Signed at North Canton, in the county of Stark, and State of Ohio, this 13th day of July, A. D., 1929.

WALTER C. DAVIDSON.
